DESIGN FOR AN ANIMATED DECORATIVE LAMP

Aubrey B. Leech, Los Angeles, Calif.

Application August 14, 1939, Serial No. 86,676

Term of patent 7 years

To all whom it may concern:

Be it known that I, Aubrey B. Leech, a citizen of the United States of America, residing at Los Angeles, in the county of Los Angeles and State of California, have invented a new, original, and ornamental Design for an Animated Decorative Lamp, of which the following is a specification, reference being had to the accompanying drawing, forming a part thereof.

Fig. 1 is a front elevation of the animated decorative lamp showing my new design and the appearance thereof when the same is illuminated.

Fig. 2 is a side elevational view of the lamp with the protective housing removed, showing the electric lamp supporting base and the cylindrical rotating screen in place.

Fig. 3 is a front elevation of the lamp taken on the line 3—3 of Fig. 2, showing the intermediate plate which cooperates with the rotor to animate the figure on the forward plate of the lamp.

Fig. 4 is a side elevation of the lamp shown on a smaller scale with the protective housing in place.

The picture is in colors and the shading and stippling on Figs. 2 and 3 are to illustrate the variations in colors and relative degrees of transparency or translucency on the plate.

I claim:

The ornamental design for an animated decorative lamp, as shown and described.

AUBREY B. LEECH.
